United States Patent Office

Des. 181,024
Patented Sept. 17, 1957

181,024

CHAIR

Milton E. Robinson, Hinsdale, Ill., assignor to The Taylor
Chair Company, Bedford, Ohio

Application April 5, 1957, Serial No. 45,606

Term of patent 7 years

(Cl. D15—1)

Fig. 1.

Fig. 2.

Figure 1 is a perspective view illustrating the front and one side of a chair embodying my new design; and

Figure 2 is a perspective view illustrating the rear and the opposite side thereof.

The dominant features of my design reside in the portions shown in full lines.

I claim:

The ornamental design for a chair, as shown and described.
